UNITED STATES PATENT OFFICE

GEORGE H. SHERWOOD, OF DENVER, COLORADO.

VESTIBULE-DIAPHRAGM FOR RAILWAY-CARS.

1,143,734.

Specification of Letters Patent. Patented June 22, 1915.

Application filed December 29, 1914. Serial No. 879,503.

To all whom it may concern:

Be it known that I, GEORGE H. SHERWOOD, a citizen of the United States, residing at Denver, in the county of Denver and State 5 of Colorado, have invented a new and useful Vestibule-Diaphragm for Railway-Cars, of which the following is a specification.

The present invention appertains to vestibule diaphragms for railway cars, and aims 10 to provide a novel and improved equipment of that character for passenger cars.

This invention aims to provide a vestibule diaphragm constructed chiefly of sheet metal, whereby the same will be durable and 15 substantial, as well as being capable of standing great wear and tear, it being well known that the fabric diaphragms now in use are the source of trouble in numerous respects, which need not be itemized at length.

20 As a more specific object, the invention aims to provide the top or overhead portion of the diaphragm with means for catching and discharging the cinders thrown up by the locomotive, whereby the cinders will not 25 accumulate within the folds or valleys of the top of the diaphragm, as would be liable to clog the same or impair its action.

It is also within the scope of the invention, to provide a sheet metal diaphragm 30 which is comparatively simple, non-encumbering and inexpensive in construction, which will adjust itself to accommodate the relative motions of the adjacent cars, and which will be thoroughly practical and effi- 35 cient in use.

With the foregoing and other objects in view which will appear as the description proceeds, the invention resides in the combination and arrangement of parts and in 40 the details of construction hereinafter described and claimed, it being understood that changes in the precise embodiment of the invention herein disclosed can be made within the scope of what is claimed without 45 departing from the spirit of the invention.

The invention is illustrated in its preferred embodiment in the accompanying drawings, wherein—

50 Figure 1 is a side elevation of the appliance as attached to the end of a passenger car. Fig. 2 is an enlarged fragmental view in section taken on the line 2—2 of Fig. 1. Fig. 3 is an enlarged plan view of the device, one of the curtains being removed. 55 Fig. 4 is a fragmental vertical section taken on the line 4—4 of Fig. 3.

In carrying out the invention, the diaphragm which is of arch-like form, comprises the bellows sides 1, and the bellows top 2, which are attached to the end of the 60 car 3, and the diaphragm face plate 4, so as to enable the diaphragm face plate 4 to move relative to the car, as usual. The bellows sides 1 are each constructed of sheet metal, and to this end, each of the sides embodies a 65 plurality or series of upright panels or plates 5, which have their edges formed with alining hinge butts 6, through which vertical hinge rods 7 are engaged, to hinge the panels 5 together. The end panels 5 are 70 hinged to the face plate 4 and the end of the car body 3. The bellows top 2 also comprises a series of sheet metal panels or plates 8 which are disposed horizontally, and the adjacent upper edges of which are formed 75 with alining hinge butts 9, through which hinge rods 10 are engaged, to hinge the adjacent upper edges of the panels together. The lower edges of the panels or plates 8, are connected by sheet metal channels or 80 gutters 11, the lower edges of the panels 8 and the edges of the channels being formed with alining butts 12, through which hinge rods 13 are engaged, to hingedly connect the lower edges of the panels 8, through the 85 medium of the channels 11, and whereby the channels 11 will be disposed at the bottoms of the valleys between the panels 8. The endmost panels 8 are hinged to the end of the car body 3 and the diaphragm face 90 plate 4.

The panels or plates of the sides and top are preferably similar in number, whereby the bellows sides and top will enable the diaphragm to expand and contract in the manner of an accordion, for permitting the diaphragm to accommodate the movements of the adjacent cars. The inner hinges of the sides 1 are preferably disposed immediately under the side edges of the top 2, or under 95 the ends of the channels 11. The panels of each set are so hinged together as to provide a tight joint therebetween, and in order that the panels may fold snugly together, or swing into a straight line or flat position 100 when the diaphragm is completely extended.

In order to close the openings between the adjacent edges of the sides and top of the diaphragm, curtains or aprons 14 of leather, canvas or other suitable material are secured 110 in any suitable manner to the under sides of the end portions of the panels 8, and hang

downwardly over the outer sides of the panels 5 of the sides. The curtains or aprons 14 will fold and unfold with the top panels 8, and the side panels 5 being moved outwardly and inwardly will carry the lower or free portions of the curtains or aprons 14 therewith.

From the foregoing, it is believed that the advantages and attributes of the present appliance should be obvious, it being noted that the diaphragm is constructed chiefly of sheet metal, to resist wear and tear, and to render it more durable than the leather or fabric diaphragms now in use, which frequently become torn and injured.

The bottoms of the channels 11 are preferably inclined, so that the cinders which drop between the panels 8 of the top 2, are caught by the channels 11 and then discharged over one side of the diaphragm, to avoid the accumulation of the cinders be-

tween the panels 8, that might be liable to impair or prevent the proper folding thereof.

What is claimed is:

1. In a vestibule diaphragm, a bellows top comprising panels having their upper edges hinged together, and channels hinged connecting the lower edges of the panels.

2. In a vestibule diaphragm, a bellows top comprising panels having their upper edges hinged together, and channels hinged connecting the lower edges of the panels, the bottoms of the channels being inclined.

In testimony that I claim the foregoing as my own, I have hereto affixed my signature in the presence of two witnesses.

GEORGE H. SHERWOOD.

Witnesses:

ARTHUR G. LA MUNYON,
JOHN DILLABOUGH.
